COMBINATION SCREW DRIVER AND
SOCKET WRENCH TOOL

Emanuel Mancuso, Los Angeles, Calif.

Application June 12, 1933, Serial No. 675,429

2 Claims. (Cl. 81—55)

This invention relates to improvements in tools and more particularly to automotive tools.

One of the objects of this invention is to provide a simple, efficient and inexpensive tool designed primarily to afford the user the opportunity to use a screw driver and a socket wrench both at the same time, if desired.

Another object of this invention is to provide a tool for convenient use in connection with overhead valves of internal combustion engines and the like, where it is necessary to effect the loosening of a nut as well as of a screw concentrically associated with the nut, which, at present calls for the use of a socket wrench in one hand and of a screw driver in another hand, with the nuisance always present of the operator jamming his fingers or injuring his hands.

A further purpose hereof is to provide, in a tool of the character described the desirable feature of quick attachment and detachment of the socket wrench adjunct from the main body of the tool to enable socket wrenches of different sizes to be employed.

Another important object of the present invention is to provide means for adjusting the screw driver in the handle of the tool to properly position the working end of the screw driver with respect to the work.

A still further object thereof is to provide means permitting play of the screw driver in a direction counter to the work, whilst the socket wrench is in engagement with the work, or with the nut to be loosened.

With the above and other objects in view my invention consists in the combination, arrangement and details of construction disclosed in the drawing and specification, and then more particularly pointed out in the appended claims.

In the drawing, wherein similar reference characters designate similar parts throughout the respective views,

Figure 1 is a fragmental plan view of my invention,

Figure 2 is a side elevation thereof,

Figure 3 is a fragmental bottom plan view thereof,

Figure 4 is an elevation, partly in section, of my invention,

Figure 5 is a fragmental top plan view of the bar handle, the screw driver being shown in section,

Figure 6 is a fragmental bottom plan view of the bar handle showing the screw driver and socket wrench holder in section,

Figure 7 is a cross-section taken on line A—A of Figure 4, and

Figure 8 is a fragmental sectional view of the screw driver shank encased in its holder.

Referring to the drawing, which is merely illustrative of my invention the parts of my invention are disclosed. A flat bar handle for operating the socket wrench is broadly designated A. The screw driver is positioned in a plane at right angles to this bar handle, the handle thereof being designated 10, the cylindrical ferrule or stub being designated 11. The main shank or stem of the screw driver is designated 12 terminating in its working end 13. Secured in spaced parallel relation with respect to the outer end of the flat bar handle A is a stepped support 14 forming a rest for the ferrule of the screw driver, this support being offset at 15 and terminating in a base portion 16 which is secured by fasteners 17 to the bar handle A.

The screw driver projects rotatably through a hole formed in the support 14, and also in a hole formed in the flat handle A, in such a manner that the ferrule 11 rests upon the support. There is a contractile spring 18 coiled around the portion of the shank 12 of the screw driver which projects between the bar handle and the support 14, this last-named portion of the shank also having a series of holes 20 formed therein, for the interchangeable selective reception of a pin 19, so that this pin may project slightly from the shank of the screw driver and rest upon the flat bar handle to prevent downward movement of the screw driver, the spring allowing the screw driver to be retracted in opposition to the spring.

As a means for detachably and releasably holding any number of tubular socket wrenches of varying sizes and shapes, I provide a polygonal tubular member 21 which is made to fit a corresponding polygonal hole formed in the flat bar handle A. The inner part of this member 21 is flush with the top face of the bar handle A, and this member has the shank 12 of the screw driver rotatably mounted in its bore, in such a way that the shank projects below the bar handle and below the member 21. A set screw 23 is employed as a means for securing the member 21 against displacement from the bar handle.

The tubular socket wrench is of standard construction and may be formed with fluted portions or serrations 24 upon its inner bore. The inner end of the socket wrench may be slightly increased in diameter and is formed at four circumferentially spaced apart points (two only of such parts being shown) with notches or cavities 29. The

- polygonal member 21 is formed externally with a rectilinear groove 27, in which one end of a leaf or sear spring 25 is secured at its inner end, the terminal of this spring being bowed as at 26 so as 5 to extend outside of the groove slightly so that it would require pressing this bowed part of the sear spring inwardly to permit the head of the socket wrench being fitted against the polygonal member 21.
- 10 In use a socket is placed on the member 21 and releasably secured thereto by its engagement with spring 25. The operator or user now fits the lower serrated portion of the socket wrench onto the nut of a valve pusher rod, and the screw which is on the end of the pusher rod receives the working end of the screw driver. The user now grasps the bar handle and gives same a turn, thereby loosening the nut, and at the same time turns the screw driver, thereby loosening the screw, the auxiliary clamp of the tool engaging 15 the pusher rod to steady the parts, I do not limit myself to the exact details of construction save as pointed out in the appended claims.
- 20 25 What I desire to claim and secure by Letters Patent is:—
1. A device as described consisting of a screw driver, a bar disposed angularly of the screw driver and receiving slidably the shank thereof, a prop secured at one end to said bar and supporting the shank of said screw driver partially above the bar, a projection below the bar rotatably receiving the shank of the screw driver, means detachably securing a socket wrench upon the projection so as to surround the working end of the shank so as to allow the shank and wrench to work together, a coiled spring enveloping the shank and engaging the prop and a pin projecting fixedly from the shank, said pin resting upon the bar to prevent downward movement of said shank, 10 and said shank being movable backward towards the prop against the tension of said spring.
2. A device as described consisting of a bar having a hole at one end a socket wrench carrier having a part detachably received in said opening, a set screw tapped into said bar and operative to lock the mentioned part to the bar, a screw driver having its shank rotatably projecting into the carrier and carrying a pin midway thereof which rests movably on the bar, a coiled spring 15 enveloping the shank having its lower end resting upon said pin, a handle on the screw driver, and rigid means carried by said bar engaging said handle to rotatably support it and being engaged by the upper end of the spring so that when the screw driver shank is raised the pin may compress the spring against said means.

EMANUEL MANCUSO.
